[57] CLAIM

The ornamental design for an electric vacuum regulator valve for use with automotive emissions control, as shown.

DESCRIPTION

FIG. 1 is a top plan view of an electric vacuum regulator valve for use with automotive emissions control showing our new design;

FIG. 2 is a front elevational view thereof;

FIG. 3 is a bottom plan view thereof;

FIG. 4 is a top, front perspective view thereof;

FIG. 5 is a right side elevational view thereof;

FIG. 6 is a left side elevational view thereof.

FIG. 1

FIG. 2

FIG. 3

FIG. 4

FIG.5

FIG.6
